(57) **CLAIM**

The ornamental design for an electrical outlet cover, as shown and described.

DESCRIPTION

FIG. 1 is a front perspective view of an electrical outlet cover, showing my new design;

FIG. 2 is a rear perspective view of the electrical outlet cover of FIG. 1;

FIG. 3 is an exploded environmental perspective view of the electrical outlet cover of FIG. 1;

FIG. 4 is a front elevation view of the electrical outlet cover of FIG. 1;

FIG. 5 is a rear elevation view of the electrical outlet cover of FIG. 1;

FIG. 6 is a side elevation view of the electrical outlet cover of FIG. 1;

FIG. 7 is a top plan view of the electrical outlet cover of FIG. 1;

FIG. 8 is a cross section view taken along line 8-8 of FIG. 4;

FIG. 9 is a front perspective view of an electrical outlet cover, showing an alternate embodiment of my new design;

FIG. 10 is a rear perspective view of the electrical outlet cover of FIG. 9;

FIG. 11 is an exploded environmental perspective view of the electrical outlet cover of FIG. 9;

FIG. 12 is a front elevation view of the electrical outlet cover of FIG. 9;

FIG. 13 is a rear elevation view of the electrical outlet cover of FIG. 9;

FIG. 14 is a side elevation view of the electrical outlet cover of FIG. 9;

FIG. 15 is a top plan view of the electrical outlet cover of FIG. 9; and,

FIG. 16 is a cross section view taken along line 16-16 of FIG. 12.

The broken lines shown represent unclaimed subject matter and form no part of the claimed design.
